(57) **CLAIM**

The ornamental design for a sensor for a monitoring or alarm system, as shown and described.

DESCRIPTION

FIG. 1 is a front view of a sensor for a monitoring or alarm system according to a first embodiment of the present invention;

FIG. 2 is a back view of the sensor for a monitoring or alarm system of FIG. 1;

FIG. 3 is a first end view of the sensor for a monitoring or alarm system of FIGS. 1 and 2;

FIG. 4 is a second end view of the sensor for a monitoring or alarm system of FIGS. 1-3;

FIG. 5 is a first side view of the sensor for a monitoring or alarm system of FIGS. 1-4;

FIG. 6 is a second side view of the sensor for a monitoring or alarm system of FIGS. 1-5; and,

FIG. 7 is a perspective view of the sensor for a monitoring or alarm system of FIGS. 1-6.

The broken line portions of the FIGS. illustrate unclaimed elements that form no part of the claimed design. Terms such as "front" and "back" are used for comparing the figures but are not limiting on the orientation of the sensor for a monitoring or alarm system.
